DRY KILN AND THE ART OF KILN DRYING

James Forrest Cobb, Portland, Oreg., assignor to
The Moore Dry Kiln Company of Oregon, a
corporation

Application January 10, 1938, Serial No. 184,284

9 Claims. (Cl. 34—26)

This invention relates to the novel method of serial charging rows of stock loads of material to be dried on individual tracks in a multiple track dryer and of drying them.

An object of my invention is to provide a more efficient dryer in which a drying atmosphere of substantially uniform entering air temperature is circulated across a series of rows of stock loads of different degrees of dryness.

Another object of my invention is to provide a more economical and more stable means for quantity drying of lower grade lumber.

Another object of my invention is to provide a novel dryer means for effecting more economical handling, more uniform drying and better quality drying than can be accomplished in ordinary dryers.

In progressive kilns now in use, loads of material to be dried are put progressively into the kiln at intervals, one behind the other, on the same track so that dryer lumber is at the dry end and greener lumber is at the green end. The temperature in the kiln increases from the green end to the dry end and the humidity decreases accordingly. Multiple track charge kilns are also in use, and in these the temperature is gradually raised as the drying period progresses.

I preferably employ a new method of drying, consisting of serially charging a full track or row of stock loads periodically into a dryer having a plurality of parallel tracks, and of circulating a common drying atmosphere across the loads, the common atmosphere having substantially the same entering air temperature throughout the entire dryer and throughout the drying period. This method reduces steam consumption, reduces the cost of drying lumber such as the common grades which are dried in quantity, reduces handling costs through the dryer, and stabilizes the drying conditions and insures high quality of the kiln dried stock.

What constitutes my invention will be more particularly pointed out in a detailed description which follows and succinctly defined in the appended claims.

In the accompanying drawings wherein my invention is illustrated in preferred form of embodiment,

Figure I illustrates in transverse vertical cross section one form of embodiment of my dryer.

Figure II is a longitudinal vertical section at II—II of Figure III.

Figure III is a plan view of Figures I and II.

Figure IV is a transverse vertical cross section of another form of embodiment of my dryer.

Figure V is a vertical longitudinal section of V—V of Figure VI.

Figure VI is a plan view of Figures IV and V.

Referring to the numerals on the drawings in each figure thereof where they appear, 1 indicates the opposite side walls of the kiln, 2 the floor, 3 the roof and 4 the end walls defining a closed chamber and constituting the outside walls of the kiln. Said walls may be of any suitable material and construction and combined in any manner preferred so as to confine within the enclosed chamber the gaseous circulatory medium with the heat and moisture which are supplied to it.

15 The end walls 4 or at least one of them are preferably made to include some means of door 5 whereby the material to be dried may be conveniently introduced into the kiln and withdrawn from it.

20 Extending lengthwise through the dryer are a series of tracks or rails 6 which are supported on the floor 2 resting on the ground as in Figure I or at suitable intervals within the kiln at a desired elevation above the floor 2 by the cross beams 7 in Figure IV. Loads 10 of material to be dried are serially charged on the tracks. One track is loaded at a time and at periodic intervals of one day, for example, and when the track is emptied of dry stock it is reloaded with 25 green stock so that the several tracks hold stock loads of different degrees of dryness.

30 The tracks are designed to support and carry wheeled trucks 8 which may be of any usual form preferred and which are united in pairs, preferably by cross beams or bunks 9, on which the lumber or material to be dried is piled endwise with boards parallel to the tracks and with transverse stickers 11 providing spaces 13 between the layers 12 of the loads 10.

35 40 In Figure I, one embodiment of my invention is illustrated employing a four track dryer with heating coils 31, 32 and 33 between the stock loads and a row of fans 14 rotated by individual reversible gear motors 15, suitably wired to a source of electrical power, for circulating the atmosphere across the series of stock loads 10 and recirculating the air above the loads through the recirculating space 55. Other arrangements of fans may be used as, for example, the arrangement illustrated in Patent No. 1,955,374.

45 50 I preferably employ a substantially uniform temperature and humidity of the entering air throughout the entire dryer. I preferably employ temperature and humidity recorder controllers 25 similar to that illustrated in Patent No.

1,624,887, with a thermostatic bulb 29 in the kiln and a diaphragm valve 27 controlling the amount of steam supplied to the heating coils 26 and 30 through the pipe 24. The heating coils 31, 32 and 33 between the loads supported by posts 17 may be supplied likewise to maintain the uniform temperature desired. Additional pipe is employed in the coils 26 and 30 of Figure IV to heat the incoming fresh air, depending upon the direction of air circulation. Each coil may be separately controlled if desired.

I preferably provide means for intake of fresh air into the kiln. For example, on two sides of the fan partition 16 illustrated in Figure I, are ventilating means as controllable air intake ports 21 and ventilators 20 joined by the rod 69 for intake and outlet respectively of atmosphere to and from the kiln when the circulation is moving in the direction of the arrows. Fresh air may be taken in on the suction side of the fans through the ports 21 of the ducts 23 and atmosphere may be exhausted from the kiln through the ports 20 of the duct 22. When circulation in the kiln is reversed, these ports are reversed in function. These may be in the side walls as doors 36 and 37 illustrated in Figures IV and VI or other usual ventilator means may be employed. By increasing the ventilation of the kiln the amount of recirculation would be reduced, depending upon the amount of relative humidity desired.

A common drying atmosphere is circulated transversely through the sticker spaces 13 across the several loads 10 on adjacent tracks so that air passing across a recently charged row of 35 green loads will pass across heating coils and then across the corresponding stock loads seriatim of different degrees of dryness on the other serially charged tracks. After the atmosphere passes across one load, it drops in temperature and is considered exit atmosphere, and after 40 passing across the adjacent heating coils which reheat it, it is known as entering air or atmosphere. In my dryer the entering air temperature for each of the rows of loads 10 is substantially the same.

When you consider the dry bulb only, the temperature may be controlled by heating pipes between loads to a definite degree before it enters each row of stock loads and this is the usual procedure. For example, considering Figure I, the atmosphere enters the first row of stock loads on the right of the fans at a temperature of 140°. In passing across the first row of loads which may be, for example, one-quarter dry, the temperature drops to 134°. The atmosphere is reheated by the heating coil 33 to 140°. In passing across the second row of loads which are, for example, about half dry, the temperature of the atmosphere drops to 136°. The atmosphere is then reheated by the heating coils 30 and 26 in the space above the loads to 140°. In passing across the third row of loads which are, for example, three-fourths dry, the temperature of the atmosphere drops to 138°. In passing across the heating coils 31, the temperature is again heated to 140°. In passing across the fourth row of loads, which are, for example, the greenest loads last placed into the kiln, the temperature drop may be to 132°. The air in passing through the heating pipes 32 is then reheated again to 140° and is ready to pass across the first load again. When automatic heat control between each row is used for individual coils, such a temperature schedule may be automatic.

Now, considering the wet bulb temperature is set at 130°. As the atmosphere passes across the first row of loads at the right of the fans in Figure I, the wet bulb temperature remains 5 unchanged as the total heat of the atmosphere remains unchanged. In passing across the heating pipes 33, however, the wet bulb temperature may be increased to 134 1/4°. In passing across the second row of loads the wet bulb temperature remains at 130 1/4°, and in passing across the heating coils 30 and 26 the wet bulb temperature may rise to 131 1/4°. In passing across the third row of loads the wet bulb temperature remains the same. In passing across the heating coil 31, the wet bulb may be increased to 131 1/2°. In passing across the fourth or greenest row of loads the wet bulb remains the same. In passing across the heating coils 32, the wet bulb tends to be raised to 132 1/2°. At this point the wet 15 bulb controller which actuates the ventilators or in some cases of manual control, the operator lets in sufficient amount of fresh air and lets out a sufficient amount of kiln atmosphere so that the atmosphere is reconditioned insofar as 20 the wet bulb temperature is concerned and the wet bulb temperature is again brought to 130°. 25

The dry bulb temperature of the atmosphere can be controlled as it enters each row of loads to maintain the same humidity of the atmosphere entering each row by setting up the dry 30 bulb temperature to give a desired humidity, or the humidity may be allowed to raise as the air passes across successive loads. My invention contemplates the variation of temperature and humidity normally occurring as the atmosphere circulates across the series of rows of loads, which vary in degree of dryness, the gradual increase of the wet bulb temperature being a factor in heating up the green stock loads on the track filled on a particular day, more quickly than if all of the tracks were charged with rows at one time, which is the usual method.

In another embodiment of my invention I provide two air circulating systems, one on each side of the dryer as illustrated in Figures IV and VI. These fan systems operate simultaneously and one supplements the other to effect a single circuit of transverse circulation across the corresponding loads on the several parallel tracks in the dryer. The atmosphere is recirculated below the loads. The recirculation space 55 may be above the loads as in Figure I or below the loads as in Figure IV. In Figures IV and VI I employ a series of reversible rotary fans 41 operatively mounted on a longitudinal shaft 42 and preferably rotated at the same speed by a suitable reversible motor 43 and drive. In Figure VI the shaft 42 rotates in bearings 44 supported by the bearing stands 46 mounted on the intermediate floor 45. Transverse air circulation is effected by means of a zigzag fan duct wall comprising walls 47, 48, 49 and 50 extending substantially from end to end of the kiln in a zigzag direction as illustrated in plan in Figure VI. The zigzag effect of the said wall is achieved by the formation of a series of alternately disposed compartments formed by the substantially parallel walls 48 and 49, the diagonal walls 50, and the apertured wall 47. Each of the walls 48, 49 and 50 is so imperforate and each of the walls 47 is provided with an aperture of suitable dimensions to accommodate within it one of the series of rotary fans 41. The walls 47, 48, 49 and 50 are united on adjacent edges 60 to form the compartments on opposite sides of

the fans. Each alternate compartment is open on one side of the zigzag wall and closed on the opposite side. By the disposition just described of the several walls 47, 48, 49 and 50, the result is in the assemblage, to impart to the wall so constituted through its entire length what is designated as a zigzag wall or effect.

The angle at which the walls 50 meet the walls 47 and 48 as shown in Figure VI is an obtuse angle on the same side, but it is obvious that the angle may be varied if desired as in some instances it may be. Each of the walls last named rests on the intermediate floor 45 of the kiln.

I prefer to use a series of right hand fans at one end of the kiln and a series of left hand fans at the opposite end of each fan system, the zigzag wall being reversed in direction at a medial portion of the kiln as shown in Figure VI. In the intermediate compartment where right and left hand fans face each other, two fans will blow against each other in counteracting currents in one direction of air circulation and withdraw atmosphere from the same compartment in the reverse direction of circulation.

In the zigzag assemblage, the walls 47, 48, 49 and 50 extend upward and connect with the partition 51 and its extension 52 the whole of which makes substantial closure with the top corner of the adjacent stock loads substantially the full length of the kiln. The assemblage of fan ducts thus forms a continuous partition through which the plurality of fans 41 circulate the kiln atmosphere. By employing two such cooperating fan duct systems, one at each side of the dryer as illustrated in Figure VI, one sucking air one side of the stock loads and the other blowing air from the opposite side of the dryer, one continuous circuit of transverse air circulation is effected across the stock loads on the plurality of tracks.

A humidifying means is provided by the steam spray pipe 60 which is preferably automatically controlled by any well known means, such as, for example, a wet and dry bulb controller 25 employing a wet bulb 39 which operates a diaphragm valve 10 on the spray line 60 by means of air pressure from a source not illustrated. The wet bulb 39 is equipped with a suitable water box 38 according to well known practice.

I preferably provide heating means 26 and 30 adjacent to each fan system for heating the fresh air taken into the kiln by admixture with the recirculated air prior to its passage through the fans, the heating systems may be divided at the two ends of the kiln where the heating systems exceed 50 feet in length.

In addition to the heating system mentioned above, I preferably provide heating means 31, 32 and 33 between the stock loads to recondition the atmosphere after it has passed across one load and before it passes across another load in either direction of air circulation.

I also preferably provide ventilating means shown in Figure IV for the outlet of moist air from the dryer and for the intake of fresh air. The controllable doors 36 in sections on the suction side and the controllable door 37 on the pressure side are reversible in function upon reversal of the air circulation and may be of sufficient size when fully open to eliminate recirculation of air in the dryer. The doors are preferably automatically operated by motor levers 66 connected to them by chains 67 by means of compressed air in the pipe 68 from a source

not shown. When the wet bulb falls below the set point, the vents 37 and air ports 36 are closed automatically. They likewise will open when the wet bulb temperature rises up to the set wet bulb temperature. The vents as well as the humidifying sprays are operated by the controller depending upon the setting of the wet bulb temperature. In the dryer illustrated in Figure I, I preferably condition the incoming fresh air before it passes across the stock loads.

Considering that both fan systems are reversible, it is intended that the air shall be circulated in one direction by both systems for a period of time, for example, twelve hours, and air circulated in the opposite direction across the loads for a similar period. The two fan systems mutually cooperate to effect uniform air circulation across the adjacent stock loads successively on the several tracks. The loads may have voids between their ends and if only one fan system is used there is more short circuiting and less uniform circulation across the stock. The two fan systems, with the stock loads all between them, effect uniform circulation and uniform drying. The discharge of air from the fan system is in jets of varying direction while the suction of the fans is uniform and when two fan systems are used, one blowing and one sucking, the circulation and drying are uniform. The reversal of air circulation also eliminates the ill effects of jets from the blowing fans as the series of blowing fans becomes a series of sucking fans upon reversal.

Suitable baffles 52 and 53 are provided to direct the air across the loads instead of allowing it to pass around them.

I preferably provide dual dry bulbs on each of the dry bulb tube systems of the controller with one bulb thereof on each side of the heating system to give control of the air entering the stock load in either direction of transverse air circulation. Two dry bulbs, for example, 29 and 29-A, are connected by capillary tubes 28 and 28-A, and capillary 34 to one actuating element such as a helical coil 19 of the instrument. See Patent No. 1,624,887. When dual dry bulbs are used, the bulb in the hottest atmosphere, that having passed across the heating coil No. 30 in Figure IV, actuates the helical coil of the controller through effecting the higher vapor pressure therein.

The operation of my dryer is as follows:

A row of loads is placed on one track preferably to fill it substantially from door to door of the dryer and the dryer is ready for starting its operation. A common drying atmosphere having substantially the same temperature is circulated transversely across the loads. Later, for example, after twelve hours, a second track is charged in a similar manner and the air is circulated across the two rows of loads. Similarly, after an equivalent interval of time, a third track is charged with stock to be dried, of the same, or different kind, thickness and moisture content. Similarly, after an equivalent interval a fourth track is charged. They are also serially recharged, usually in the same order, at regular intervals, for example, of twelve hours, twenty-four hours or thirty-six hours, as one row of loads becomes sufficiently dry. The temperature remains the same throughout the drying schedule. When the stock is dried down to a desired moisture content, as determined by inspection or moisture content tests, it is removed from the dryer and that track is recharged with new

material to be dried. For example, in a four track dryer the time schedule or the interval between the charging of different tracks is usually one-fourth of the drying period.

In the ordinary progressive dryer wet stock is put in at one end and it is progressed through the dryer in stages, the wetter stock following the stock ahead of it and the temperature and humidity being changed as drying progresses. It is not possible to remove any of the stock except that at each door without discharging the entire kiln. Each time a load of stock is put into a progressive kiln all the loads must be moved in the kiln, which involves considerable labor. In my dryer the stock on any one track is removed and replaced at regular intervals and only the row of loads put in or removed are handled. The other loads are not disturbed. This reduces the cost of handling the stock loads in my dryer. Also in my dryer a common atmosphere of uniform temperature is circulated across the loads of each track of varying moisture content and stages of dryness.

The coils between the loads may be automatically controlled, if desired, to maintain a predetermined dry bulb temperature of the atmosphere after it has passed across the loads on one track and before it passes across the loads on the adjacent track.

It is understood that this invention is not limited to the exact design and form illustrated and described. Modifications of the methods and structures herein described and mechanical equivalents are self-evident to those skilled in the art; therefore, it is to be understood that the invention includes within its scope whatever changes fairly come within either the terms or the spirit of the appended claims.

Having described my invention, what I claim is:

1. The method of kiln drying lumber which consists of serially charging into an enclosure air permeable stock loads of lumber in spaced parallel rows on tracks, one row at a time at substantially regular time intervals, so that each row of stock loads has been dried a different amount from the other rows, circulating a common atmosphere through the rows of loads laterally from one side of the kiln to the other and in part back to the first mentioned side in recirculation, reconditioning the atmosphere between each row and replacing each row when it is dry with a green row.

2. The method of kiln drying lumber which consists of serially charging into an enclosure lumber in spaced parallel rows of air permeable stock loads on tracks, one row at a time at substantially regular time intervals, so that each row of stock loads has been dried a different amount from the other rows, circulating a common atmosphere through all of the rows seriatim and reconditioning the atmosphere between each row of loads to maintain a substantially constant temperature of kiln atmosphere which enters a stock load, and replacing each row when it is dry with a green row.

3. The method of kiln drying lumber which consists of serially charging into an enclosure lumber in spaced parallel rows of air permeable stock loads on tracks, one row at a time at substantially regular time intervals, so that each row of stock loads has been dried a different amount from the other rows, circulating a common kiln atmosphere through all of the rows seriatim, reconditioning the atmosphere between

each row of loads to maintain a substantially constant temperature of kiln atmosphere which enters a stock load, and continuing a substantial portion of the atmosphere movement from the outlet side of the last row to the inlet side of the first row, and replacing each row when it is dry with a green row.

4. The method of kiln drying lumber, which consists of serially charging into an enclosure, 10 lumber in spaced parallel rows of air permeable stock loads on tracks, one row at a time at substantially regular time intervals, so that each row of stock loads has been dried a different amount from the other row, taking in outside atmosphere, mixing it with kiln atmosphere and circulating the mixture through the rows seriatim, 15 reconditioning the atmosphere between each row of loads to maintain a substantially constant temperature of kiln atmosphere which enters a stock load, venting a portion of the atmosphere after it has passed across all the rows of loads, and replacing each row when it is dry with a green row.

5. The method of kiln drying lumber, which consists of serially charging into an enclosure, 20 lumber in spaced parallel rows of air permeable stock loads on tracks, one row at a time at substantially regular time intervals, so that each row of stock loads has been dried a different amount from the other row, taking in outside atmosphere, and circulating it through the rows seriatim, reconditioning the atmosphere between each row of loads to maintain a substantially constant temperature of kiln atmosphere which enters a stock load, venting said atmosphere after it has passed across all the rows of loads, and replacing each row when it is dry with a green row.

6. In a multiple track dryer, a housing having 25 within it a plurality of spaced tracks for the accommodation of end piled rows of air permeable stock loads thereon, a recirculation passageway having heating means therein, heating means between adjacent rows of stock loads, air 30 circulating means between two of the rows of stock loads and comprising a plurality of reversible fans for recirculating a common drying atmosphere across all of said rows of loads, and through said recirculation passageway and across the heating means therein, a ventilator and an air port for each of said fans, said ventilator and air port having conduits extending through the dryer housing to the opposite sides of said fans and adjacent thereto in operative communication with them, said fans being reversible in function when the fans are reversed, heating means between the fans and the adjacent load on each side of the fans, whereby incoming fresh air is heated before passing across the loads in each direction of circulation, and a controller for one of said last named heating means, said controller having dual dry bulbs, one of said bulbs being on one side of said heating means, and the other bulb being on the opposite side thereof.

7. The method of drying which consists of serially charging into an enclosure a series of 35 rows of air permeable stock loads of material to be dried in spaced relationship, one row at a time at substantially regular time intervals so that each row of stock loads has been dried a different amount from the other rows, of recirculating a drying atmosphere across all of the rows of loads, of venting a portion of the circulating atmosphere and replacing it with fresh air, of conditioning the common atmosphere as it

passes from one row of loads to another in recirculation to maintain a substantially uniform temperature of the atmosphere which enters a stock load and a minimum relative humidity throughout the drying period for all of the stock loads, and of replacing each row when it is dry with a green row.

8. The method of drying which consists of serially charging into an enclosure a series of rows of air permeable stock loads of material to be dried in spaced relationship, one row at a time at substantially regular time intervals so that each row of stock loads has been dried a different amount from the other rows, of recirculating a drying atmosphere across all the rows of loads, of venting a portion of the circulating atmosphere and replacing it with fresh air, of conditioning the common atmosphere as it passes from one row of loads to another in recirculation to maintain a substantially uniform temperature of the atmosphere which en-

ters a stock load, and of replacing each row when it is dry with a green row.

9. The method of drying which consists of serially charging into an enclosure a series of rows of air permeable stock loads of material to be dried in spaced relationship, one row at a time at substantially regular time intervals so that each row of stock loads has been dried a different amount from the other rows, of recirculating a drying atmosphere across all the rows of loads, of venting a portion of the circulating atmosphere and replacing it with fresh air, of conditioning the common atmosphere as it passes from one row of loads to another in recirculation to maintain a substantially uniform temperature of the atmosphere which enters a stock load, of reversing the direction of the circulation across the series of loads at will, and of replacing each row when it is dry with a green row.

JAMES FORREST COBB.
